UNITED STATES PATENT OFFICE.

JOHN T. TODD, OF SPRINGFIELD, ILLINOIS, ASSIGNOR TO THE REGISTERED TRACER SYSTEM, OF SPRINGFIELD, ILLINOIS, A CORPORATION OF ILLINOIS.

CONTAINER.

1,176,183.

Specification of Letters Patent.

Patented Mar. 21, 1916.

Application filed December 10, 1914. Serial No. 876,403.

To all whom it may concern:

Be it known that I, JOHN T. TODD, a citizen of the United States, residing at Springfield, in the county of Sangamon and 5 State of Illinois, have invented certain new and useful Improvements in Containers, of which the following is a specification.

This invention relates in general to improvements in containers particularly adapted though not necessarily limited in its use 10 for containing coins and the like.

More particularly the invention relates to a container having an opening through which the contents may be removed and 15 which opening is adapted to be closed by a flap or element flexibly connected with the container and foldable over the opening and secured in position by means of a seal or sticker which latter is adapted to be broken 20 or torn by raising the flexible closing element with respect to the container.

To the attainment of these ends and the accomplishment of other new and useful objects as will appear, the invention consists in the features of novelty in substantially the construction, combination and arrangement of the several parts hereinafter 25 more fully described and claimed and shown in the accompanying drawings, illustrating the invention and in which—

Figure 1 is a perspective view of a device of this character constructed in accordance with the principles of this invention and showing the closing element secured 35 against opening. Fig. 2 is a front elevation with the seal for the closing element omitted. Fig. 3 is a vertical sectional view taken on line 3—3, Fig. 1. Fig. 4 is a detail plan view showing the closing element unfolded with respect to the container to permit the contents of the container to be removed.

Referring more particularly to the drawing and in the present exemplification of 45 this invention, the numeral 10 designates generally a container which is preferably flat and is of any desired size and configuration and constructed of any suitable material. This container is provided with a slot 50 11 in one edge thereof and through which slot the coins are adapted to be inserted thereinto, there being, if desired, a tubular element 12 inserted into the slot through which the coins pass and which element is 55 of such a construction, as to permit the coins

to be inserted into the container but to prevent their removal through the opening 11, similar to the structure shown in my United States Patent No. 1112040, September 29th, 1914. The specific construction of this tubular element 12, however, forms no part of the present invention. The container is also provided in one of its edges with another slot or opening 13, preferably arranged in the edge opposite to the edge in which the opening 11 is arranged.

An extension 14 is formed on or flexibly connected with one of the walls of the container and is of any desired length to form a flap. This flap is of a width substantially 70 equal to the length of the opening 13 and is adapted to be folded over the opening so as to rest flat against one of the faces of the container and thereby form a closure for the opening 13. 75

If desired the container may be so constructed that the wall with which the flap 14 is connected may be provided with portions 15, 16 which overlap one edge of the container so as to rest flat against the face of 80 the opposite wall. These flaps 15, 16 terminate short of each other to form an opening 17 into which the closure flap 14 may be folded and the flap 14 is preferably of a length somewhat greater than the flaps 15, 16 so 85 that the extremity 18 of the flap will project beyond the edges of the flaps 15, 16 to form a hand hold by means of which the operator may raise the flap to uncover the opening 13. 90

In order to seal the flap or closure 14 and consequently the opening 13, closed, a sealing element 19 is provided, and which element may be constructed of destructive material which will permit it to be torn or 95 broken when the flap 14 is raised, but which is of sufficient strength to hold the flap against accidental opening.

The element 19 is preferably in the form of a sticker and is of sufficient length so as 100 to extend across the face of the flap 14 to be secured thereto and projects beyond the edges thereof to be secured to the flaps 15, 16 and the flap 18 entering the opening 17, will cause its outer face to stand substantially flush with the outer faces of the flaps 15, 16. 105

With this improved construction, it will be manifest that the container may be filled with coins and after it has been thus filled 110

or when it is desired to remove the contents of the container, all that is necessary is to grasp the extremity of the flap or closure 14 with one hand and hold the container 10 in the other hand, then pull the flap 18 away from the container and as the flap is detached from the face against which it rests this action will tear or break the sealing element 19 to permit the flap to be opened 10 to the position shown in Fig. 4 to uncover the opening 13 and thereby permit the contents to be readily removed. The container can be used an indefinite number of times without mutilating the flap by folding the 15 flap 18 each time it is desired to close the opening, into the position shown in Fig. 2 and placing a new seal or sticker 19 thereon in the manner shown in Fig. 1. This flap or closure 14 and the opening 17 may be of 20 any desired shape and while the invention is described as being applicable for the use of holding coins or the like, it is obvious that it may be adapted for many other purposes and instead of having a short opening 25 13, the opening may be of any length within the limits of the container and the flap may be of a corresponding size that this opening may be sealed when desired.

What is claimed as new is:

- 30 1. A substantially flat and closed casing for receiving the coins, one of the walls of the casing extending beyond the edge of the opposite wall and shaped to form separated flaps, the outer flaps being folded over the 35 edge of the opposite wall of the casing and permanently secured to the outer face of said wall to form a narrow opening between the secured flaps and through which opening the coins may be removed, the intermediate 40 flap being free to be folded back and forth over the opening to open and close the same

an indefinite number of times, said intermediate flap foldable into the space between the outer flaps and projecting beyond the extremities of the latter when folded 45 against the casing wall, and a fragile sealing strip connected with the intermediate flap and adapted to be fastened against the casing, there being also an entrance opening to the casing for coins. 50

2. A substantially flat and closed casing for receiving coins, one of the walls of the casing having portions extending beyond the opposite wall to form flaps, the said flaps being folded over the edge of the opposite wall and permanently secured to the outer face of the latter wall and terminating short of each other to form a space therebetween, said casing being provided with an outlet opening for the coins, an additional flap formed on one of the walls and being separated and detached from the first said flap and also being of a size to cover said opening and foldable back and forth over the opening to open and close the latter 60 65 an indefinite number of times and into the space between the first recited flaps to substantially fill said space, said additional flap being unsecured to the face of the casing wall, and a fragile sealing strip secured 70 transversely of the said additional flap to project therebeyond and secured to the casing, there being an inlet opening to the casing.

In testimony whereof I have signed my 75 name to this specification, in the presence of two subscribing witnesses, on this 30th day of November A. D. 1914.

JOHN T. TODD.
